UNITED STATES PATENT OFFICE

97,183

DESIGN FOR A GAME TABLE

Herman L. Feldblet and Oscar Goldberger, New York, N. Y., assignors to Rotor-Table Games, Inc., New York, N. Y., a corporation of New York

Application August 21, 1935, Serial No. 58,227

Term of patent 14 years

To all whom it may concern:

Be it known that we, Herman L. Feldblet and Oscar Goldberger, citizens of the United States and residing in the city, county, and State of New York have invented a new, original, and ornamental Design for a Game Table, of which the following is a specification, reference being had to the accompanying drawing, forming a part thereof.

In the drawing:—

Fig. 1 is a front elevation of a game table, showing our new design.

Fig. 2 is a top view thereof.

Fig. 3 is a side elevation.

We claim:

The ornamental design for a game table substantially as shown.

HERMAN L. FELDBLET.
OSCAR GOLDBERGER.
